CHARLES R. GOW, OF WEST ROXBURY, AND LINTON HART, OF BROOKLINE, MASSACHUSETTS, ASSIGNORS TO CHARLES R. GOW COMPANY, OF BOSTON, MASSACHUSETTS, A CORPORATION OF MASSACHUSETTS.

MAKING CONCRETE FOUNDATION PIERS AND THE LIKE.

Application filed May 11, 1923. Serial No. 638,172.

This invention relates to the construction or formation of concrete piers or columns in situ for foundations and other purposes, and its chief object is to provide an effective and simple method by which such columns of adequate strength and bearing capacity can be constructed at low cost through water bearing soil. In carrying out the invention in the preferred manner the operation is begun by sinking into the ground a series of removable concentric steel shells of successively smaller diameter, one inside of the other; the largest being driven down first, then the second inside of the first, the third inside of the second, and so on, through the non-waterbearing or dry part of the soil. After each shell is driven, and before the next is sunk, the material enclosed by the driven shell is removed, so that a hole is produced having a temporary lining of steel which effectually prevents caving or slipping and therefore permits working close to existing foundations without injury thereto. When the waterbearing layer or stratum is reached or approached (as may be known by seepage or by previous sinkings or borings) the sinking of the casting shells ceases and in the lowermost a concrete lining cylinder is established, fitting the shell snugly, and, if desirable or necessary, sealed thereto by suitable packing or filling in any convenient manner to exclude water. This concrete cylinder, which is left permanently in the ground may be cast in place or it may be cast outside and inserted into the shell at the proper time. In the concrete cylinder an air lock is placed, through which air pressure is applied below the lock to prevent excessive seepage. Excavation is now continued below the lock, and as the shaft deepens its sides are covered or lined with wood, metal, or other sheathing sufficiently firm and tight to prevent caving in of the walls or inflow of soft material. This operation is carried down to the rock or hard bearing material on which the pier is to rest. While the air pressure is maintained the sheathed portion of the hole is filled with concrete and the filling carried up into the concrete lining cylinder far enough to serve as a seal against excessive seepage into the cylinder from below. As soon as the concrete is sufficiently hard to make the seal effective the air pressure is

relieved and the air lock removed. The filling is now continued in the open air, and as the filling proceeds the steel shells are withdrawn from the hole for re-use, the concrete lining cylinder, however, being left permanently in the ground.

The method outlined above is illustrated in various stages in the accompanying drawings, in which—

Fig. 1 is a vertical section showing the shaft completed down to rock or bearing material, ready for the concrete seal.

Fig. 2 is a similar section showing the concrete seal in place, the air lock having been removed.

Fig. 3 is a vertical section showing the completed pier or column.

Fig. 4 is a detail vertical section showing the lower or bearing end of the column, provided with an enlarged footing to distribute the load over a larger area of the rock or bearing material.

As indicated in the drawings, the steel shells 10, 11, 12, of any suitable size and preferably cylindrical in form, are of successively smaller diameter so that one can descend through the other. They are used to provide a temporary lining for the upper part of the hole, being eventually removed as explained hereinafter. The largest shell is first driven or otherwise sunk in the ground, followed by the others in order, the soil in the last driven being removed before the next is sunk. Three such shells are shown, but of course the precise number is immaterial, and depends upon the length of the individual sections or shells and the depth at which seepage or inflow becomes or would become excessive. When such point is reached the sinking of the lining shells ceases, and a hollow concrete lining cylinder or caisson 13 is established in the lowermost shell. This caisson or cylinder may be cast outside and inserted into the hole, or it may be cast in place. Preferably it is longer than the shell and is sunk some distance below the same, as by excavating under it, but in most cases it should project into the shell, so as to prevent excessive seepage or inflow of water or soft material at a later stage of the work. If the caisson, which is to constitute a part of the permanent lining of the hole, and may contain reinforcing members (not shown) in

its walls, is cast in place removable forms (not shown) may be used if necessary or desirable to make a caisson of the desired length, or, in some cases, if conditions permit, the ground below the lowest shell can be excavated and the bare earth sides of the hole can serve as the outer form or mold below the shell. If necessary or desirable, the caisson may be calked or packed in place 10 in any convenient and suitable manner, not shown.

When the walls of the lining caisson are sufficiently hard an air lock, shown diagrammatically at 14, is positioned therein, far enough above the bottom to permit excavation to be carried on under it by any method suited to the existing conditions. Air is pumped into the air lock and through the same into the caisson below, and sufficient 20 pressure is maintained to prevent the work being interfered with by excessive seepage.

As the hole below the caisson is deepened its sides are lined or sheathed with lining members 15, made of wood, metal, or other 25 material. These members may be segmental in form so as to be arranged end to end circumferentially, and of course are of a size to permit their introduction through the air lock. Continuing the excavation and 30 sheathing of the hole, under the necessary air pressure, until rock or hard bearing material 16 is reached, we then have the stage illustrated in Fig. 1, the hole being lined all the way down to prevent caving or slippage 35 and under sufficient internal air pressure to prevent undue seepage.

We now introduce concrete 17, through the air lock and fill the sheathed portion of the hole, preferably carrying the filling up 40 into the open lower end of the caisson, as indicated in Fig. 2, far enough to insure against excessive inflow of water from below after the air pressure is relieved. When the concrete, which serves afterward as the 45 lower portion of the column, has set hard enough to enable it to serve as a seal which will exclude undue seepage, the air lock is removed and the concrete filling is continued to the desired height. As the filling 50 is carried up, the steel shells 13, 12, etc., are pulled out in advance, one after the other. The lowest shell can usually be pulled before or after the caisson 13 is filled, and in some cases before the hole below is excavated. In most cases the shell next above 55 is withdrawn as soon as the caisson is filled, then the hole left by the shell withdrawn is filled and the work continued in this manner until the filling is completed and the last 60 shell pulled out. In some situations, as for example where excessive lateral pressures are encountered, it may be necessary to let the successive fillings set firmly enough to resist such pressures before pulling the shell next above. In this way it is sometimes 65

possible to remove all the shells under conditions which would otherwise make such course dangerous if not impossible.

Below the caisson the sides of the excavation, and hence the sides of that portion of the completed pier, may be substantially parallel, as indicated in Figs. 1, 2 and 3, or they may have more or less spread or downward flare, beginning at any desired point. Thus in Fig. 4 is shown the lower portion of a pier or column with the flare beginning a short distance above the rock 16, to form a belled or enlarged footing by which the total load is distributed over a larger area and the load per unit area thereby decreased.

It is to be understood that the operations described in the foregoing constitute the preferred practice, but that the invention can be carried out in other ways without departure from its spirit as defined by the following claims.

We claim—

1. In a method of forming concrete piers and the like in situ, sinking into the ground through each other a series of shells of successively less diameter and removing the soil from each shell before the next is sunk, thereby forming a hole having a temporary lining capable of resisting caving and slippage due to lateral pressure; establishing in the lowest shell a permanent lining section in the form of a hollow concrete caisson and by air pressure therein preventing undue seepage from below; excavating below the permanent lining section to the desired depth and lining the sides of the excavation, while maintaining an air pressure adequate to prevent excessive seepage; depositing concrete in the hole and maintaining the air pressure until the concrete has set firmly enough to seal the concrete lining section against undue seepage or the like; and thereafter relieving the pressure and filling the concrete lining and the hole above, and withdrawing the shells from the ground in succession as the filling proceeds.

2. In a method of forming concrete piers and the like in situ, sinking in succession, through each other into the ground, a series of removable concentric shells of successively smaller diameter and removing the soil from the shells as the sinking thereof proceeds; establishing in the lower shell a hollow lining section to seal the hole, excavating below the caisson to the desired depth and sheathing the sides of the excavation, and thereafter filling the hole with concrete to form a pier of the desired height, and withdrawing the lining shells.

3. In a method of forming concrete piers and the like in situ, sinking in succession, through each other into the ground, a series of removable shells of successively smaller diameter and removing the soil therefrom to form a temporarily lined hole, establish-

ing in the lower shell a hollow caisson to seal the hole and forming a permanent lining for a part of the hole, extending the hole below the caisson by excavating under air pressure adequate to prevent undue inflow of water, and sheathing the sides of the excavation to maintain the walls thereof; depositing concrete in the hole below the caisson and allowing the concrete to harden under pressure until firm enough to permit the pressure to be relieved; and thereafter continuing the filling in the open air.

4. In a method of forming concrete piers and the like in situ, sinking into the ground in succession a series of removable shells and removing the soil therefrom to form a lined hole, establishing a lining caisson therein, extending the hole below the caisson by excavating below the same under air pressure through an air lock in the caisson while maintaining the walls of the excavation against caving or the like, filling the hole below the caisson with concrete, and when the same has hardened sufficiently relieving the air pressure, and thereafter continuing the filling and removing the shells in succession as the filling is extended into the shell-lined portion of the hole.

5. In a method of forming concrete piers and the like in situ, sinking into the ground in succession a series of removable shells and removing the soil therefrom to form a temporarily lined hole, establishing a hollow concrete caisson therein to serve as a permanent lining for a portion of the hole and applying air pressure through the caisson to exclude excessive inflow of water from below, deepening the hole below the permanently lined portion by excavating below the same under said air pressure, and sealing the lower end of the caisson with concrete to prevent undue inflow into the same after the air pressure is relieved.

6. In a method of forming concrete piers and the like in situ, sinking into the ground a series of shells and removing the soil therefrom, establishing a caisson therein and applying air pressure through the lining cais-

son to prevent excessive inflow of water from below, deepening the hole below the lining caisson by excavating below the same under said air pressure and lining the deepened portion to maintain the walls thereof against collapse, filling the said deepened portion of the hole with concrete and sealing therewith the lower end of the lining caisson to prevent undue inflow after the air pressure is relieved, and thereafter filling the hole with concrete in the open air.

7. In a method of forming concrete piers and the like in situ, forming in the ground a hole having a temporary lining down to a point where further deepening of the hole would cause excessive inflow of water, establishing a lining caisson therein and applying air pressure through the caisson to prevent said excessive inflow, excavating under air pressure below the caisson to deepen the hole and maintaining the walls of the deepened portion against collapse, depositing concrete in said deepened portion and under said air pressure sealing with the concrete the lower end of the caisson to prevent excessive inflow of water after the air pressure is relieved, and thereafter in the open air filling the hole with concrete above the seal.

8. In a method of forming concrete piers and the like in situ, forming a hole in the ground and providing the same with a temporary lining composed of removable lining members, establishing in the lower portion of the temporary lining a permanent lining section of concrete, excavating below the permanent lining section to deepen the hole, sealing the said deepened portion of the hole and the bottom of the permanent lining section with concrete to exclude water, and filling the permanently and temporarily lined portions with concrete and removing the removable lining members from the upper portion of the hole.

In testimony whereof we hereto affix our signatures.

CHARLES R. GOW.
